UNITED STATES PATENT OFFICE.

EDWIN P. NORWOOD, OF CHICAGO, ILLINOIS.

DESIGN FOR A DOLL.

Application filed August 1, 1923. Serial No. 6,915. Term of patent 3½ years.

To all whom it may concern:

Be it known that I, EDWIN P. NORWOOD, a citizen of the United States, and a resident of Chicago, Illinois, have invented a certain new, original, and ornamental Design for a Doll, of which the following is a specification, reference being had to the accompanying drawing, forming part thereof.

The figure is a face view of my new design for a doll.

I claim:—

The ornamental design for a doll, substantially as shown.

EDWIN P. NORWOOD.
